US00D811352S

(12) **United States Design Patent** (10) Patent No.: **US D811,352 S**
Lee et al. (45) Date of Patent: ** Feb. 27, 2018

(54) **HOME AUTOMATION DEVICE
CONTROLLER**

(71) Applicant: **LG ELECTRONICS INC.**, Seoul (KR)

(72) Inventors: **Hophil Lee**, Seoul (KR); **Kyoungjoung Kim**, Seoul (KR); **Bonghui Kang**, Seoul (KR)

(73) Assignee: **LG Electronics Inc.**, Seoul (KR)

(**) Term: **15 Years**

(21) Appl. No.: **35/502,221**

(22) Filed: **Jul. 6, 2016**

(80) **Hague Agreement Data**

Int. Filing Date: **Jul. 6, 2016**

Int. Reg. No.: **DM/091643**

Int. Reg. Date: **Jul. 6, 2016**

Int. Reg. Pub. Date: **Jan. 6, 2017**

(30) **Foreign Application Priority Data**

Jan. 14, 2016 (KR) 30-2016-0001845

(51) **LOC (11) Cl.** **13-03**

(52) **U.S. Cl.**

USPC **D13/171**

(58) **Field of Classification Search**

USPC D13/171, 162, 108, 168, 174, 158; D14/218, 356, 228, 223, 205; D22/108; D24/187; 200/513, 302.2

CPC H01H 13/702; H01H 23/143

See application file for complete search history.

(74) Attorney, Agent, or Firm — Birch, Stewart, Kolasch & Birch, LLP

(57) **CLAIM**

The ornamental design for a home automation device controller, as shown and described.

DESCRIPTION

1. Home automation device controller

1.1 is a perspective view;

1.2 is a front view;

1.3 is a back view;

1.4 is side view;

1.5 is a side view;

1.6 is top view;

1.7 is a bottom view;

1.8 is a perspective view shown in an environment; and

1.9 is another perspective view shown in an environment.

In the reproductions, the broken lines are for the purpose of illustrating environment only and form no part of the claimed design.

1 Claim, 9 Drawing Sheets
